UNITED STATES PATENT OFFICE

118,424

DESIGN FOR A BAG PACKAGE OR SIMILAR ARTICLE

Hans O. Irmscher, New York, N. Y., assignor to Millie Patent Holding Co., Inc., a corporation of
New York

Application May 26, 1938, Serial No. 77,407

Term of patent 14 years

To all whom it may concern:

Be it known that Hans O. Irmscher, a citizen of the United States and resident of New York city, in the county of Bronx and State of New York, has invented a new, original, and ornamental Design for a Bag Package or Similar Article, of which the following is a specification, reference being had to the accompanying drawing forming part thereof, in which,

Fig. 1 is a front elevational view of a bag package or similar article showing my new design.

Figs. 2, 3, 4 and 5 are side elevational, top, bottom and rear elevational views, respectively, of said bag package or similar article, with the string handle and tag shown in dotted lines in Fig. 1 omitted.

The dominant feature of the design resides in the portion shown in solid lines.

I claim:

The ornamental design for a bag package or similar article, as shown and described.

HANS O. IRMSCHER.
